UNITED STATES PATENT OFFICE.

MILLIE M. DEIBEL, OF YOUNGSTOWN, OHIO.

COMBINED MATCH SAFE, WIND-SHIELD, AND STRIKER.

1,266,227.

Specification of Letters Patent. Patented May 14, 1918.

Application filed December 1, 1917. Serial No. 204,857.

To all whom it may concern:

Be it known that I, MILLIE M. DEIBEL, a citizen of the United States, and resident of Youngstown, in the county of Mahoning 5 and State of Ohio, have invented certain new and useful Improvements in Combined Match Safes, Wind-Shields, and Strikers, of which the following is a specification.

The present invention relates to match 10 boxes, and more particularly to the type provided with means for facilitating the lighting of a cigar or cigarette.

An object of the present invention is to provide a match box embodying in its structure a compartment for the reception of the end of the cigar or cigarette to be lighted, and to receive the head end of a match and provide means within the compartment for igniting the match; the casing or body of 20 the device being so formed as to provide compartments within which matches may be conveniently carried in position with their heads out of contact with the walls of the lighting compartment.

25 The invention also aims to provide an improved structure comprising relatively few parts which may be easily assembled and which form a strong and durable holder and light protector.

30 The above and various other objects and advantages of this invention will be in part described and in part understood from the following detailed description of the present preferred embodiment, the same being illustrated in the accompanying drawings where-

35 Figure 1 is a longitudinal transverse section taken through a match box constructed according to the present invention, and 40 showing the same in use with the end of a cigar in the lighting compartment and a burning match in the compartment applied to the cigar.

45 Fig. 2 is a longitudinal section through the match box, taken edgewise through the same and showing the large opening leading to the lighting compartment through which the cigar may be projected.

50 Fig. 3 is a side elevation of the match box of this invention, showing the side thereof

through which the match to be struck may be projected.

Fig. 4 is a similar view, showing the side thereof through which the cigar may be projected. 55

Fig. 5 is a transverse section taken through the lower end of the match box, showing the arrangement of the partition with its marginal edges seated in the grooves in the casing. 60

Referring to this drawing the device comprises a casing made up of a pair of side walls 10 and 11 joined by edge walls 12 forming a substantially rectangular body open at opposite ends. The body is preferably constructed of sheet metal in any suitable manner for facilitating assembly of the parts. The casing or body is provided therein with a substantially inverted V-shaped partition 13 formed of a strip of 70 sheet metal having its lower diverging ends offset outwardly from each other to form tongues 14 adapted to lie flat against the inner faces of the edge walls 12. 65

The sides 10 and 11 are provided with outwardly pressed beads 15 which not only reinforce and brace the casing, but which form downwardly diverging grooves in the inner faces of the side walls 10 and 11 in which are seated the lateral edge portions of the 80 strip or partition 13. The beads 15 follow the shape of the free ends of the partition 13 to firmly hold the latter in the casing and seal the partition therein. 75

The upper ends of the beads 15 merge into 85 a circumscribing bead 16 pressed outwardly from the casing near its upper end, and also merge into a second annular outstanding bead 17 near the lower end of the casing. The upper and lower ends of the casing are 90 preferably offset inwardly to form flanges 18 adapted to receive thereover caps 19 and 20 which close the inner and outer compartments respectively located at opposite sides of the partition 13. The caps may be hinged 95 upon transverse pins 21 and are adapted to yieldingly bind over the flanges 18 for frictionally retaining the caps in position.

The outer compartment, which is the upper compartment, is adapted to receive 100

therein against the outer sides of the partition 13 matches A with the heads thereof projecting above the partition 13 and into the cap 19. The diverging walls of the partition provide means for holding the matches in stepped relation so that the heads thereof may be individually grasped by the fingers when the cap 19 is raised. The heads are also thus supported above the partition 13.

The inner or lower compartment is provided with a cigar receiving opening 22 formed in one side wall of the casing, the wall 10 having the opening therethrough in the present instance. The end of the cigar B to be lighted is projected through this opening 22 into the inner compartment. The said wall 10 is provided with a roughened surface 23 located below the opening 22 and adapted to receive thereagainst the head of one of the matches A which may be projected through a match receiving opening 24 formed in the opposite side wall 11 of the casing. The opening 24 is located below the transverse plane of the opening 22 and is of sufficient size to freely receive the match A therethrough and admit the manipulation of the match for moving the head thereof against the roughened surface 23. Access may be gained to the lighting compartment for cleansing and facilitating the removal of accumulations therefrom. The device requires no adjustment of the parts to adapt it for use as a wind shield or protector for the burning match while igniting the cigar.

The use of the device is apparent, for when it is desired to light the cigar B, it is only necessary to swing the cap open, with draw a match, close the cap, project the end of the cigar B into the lighting compartment through the opening 22, and extend the match into the lighting compartment below the end of the cigar through the opening 24, the match being rocked in the opening 24 with the head of the match bearing against the igniting surface 23. The match is thus lighted, and the flame rises against the end of the cigar, lighting the same. The openings 22 and 24 admit sufficient air to promote combustion of the match A and at the same time exclude wind from the compartment which would otherwise blow the match out.

The device is relatively small and compact, and is of approximately of the size of the ordinary match box in use, presents a strong and durable structure and requires no further adjustment of its parts than the opening and closing of the cap 19 to withdraw the match. The caps 19 and 20 afford top and bottom finger holds by means of which the device may be easily held in position as shown in Fig. 1. By placing the

cigar receiving opening 22 in one side of the 65 casing and the match receiving opening 24 in the other side of the casing the latter may be held between the forefinger and the thumb of either hand and the match A readily held in the other hand and manipulated irrespective of which hand supports the casing.

It is of course understood that various changes and modifications may be made in the details of construction and design of 75 the above specifically formed device without departing from the spirit of this invention, the changes and modifications being restricted only by the scope of the following claims.

What is claimed is:

1. A combined match safe and windshield comprising, a casing open at opposite ends, a V-shaped partition arranged transversely and longitudinally in the casing forming 85 inner and outer compartments opening through the opposite ends of the casing, caps closing the opposite ends of the casing and the respective compartments and adapted to house a plurality of matches in one of the compartments, said casing having in one side a relatively large opening through which an end of a cigar may be projected into the other compartment, the casing having a relatively small opening in its opposite side through which a match may be projected into said second compartment, and means within the second compartment for 90 igniting the match.

2. A combined match safe and windshield 100 comprising, a sheet metal casing substantially rectangular in cross section and open at opposite ends, the opposite lateral walls of the casing having outwardly pressed beads extending longitudinally in the walls, 105 a partition strip arranged in the casing with its lateral edges seated in said beads to hold the partition longitudinally in the casing and divide the same into a pair of independent compartments, said partition extending 110 obliquely to the longitudinal axis of the casing to extend said compartments longitudinally of the casing and to open the compartments each through an end of the casing, caps on the opposite ends of the casing for 115 independently closing the compartments, said casing having cigar and match receiving openings leading to one compartment for admitting lighting of the cigar therein.

3. A combined match safe and windshield 120 comprising, an elongated casing provided with registering outwardly pressed beads in its opposite walls diverging from end to end of the casing, a returned partition strip seated at its opposite edges in said beads and 125 dividing the casing into inner and outer longitudinal compartments opening through the respective ends of the casing, caps on

the opposite ends of the casing for independently closing the compartments, one side of the casing having an enlarged opening leading to the inner compartment and 5 the other side of the casing having a relatively small opening, the large opening admitting the introduction of the end of a cigar into said inner compartment through one side of the casing and the smaller open-

ing admitting the introduction of a match 10 into the opposite side of the casing, said casing also having on its inner wall beneath the cigar receiving opening a match igniting surface and the smaller opening being arranged below the transverse plane of the 15 larger opening.

MILLIE M. DEIBEL.
